UNITED STATES PATENT OFFICE.

JAMES H. DYETT, OF BUFFALO, NEW YORK, ASSIGNOR TO HARD MANUFACTURING CO., OF BUFFALO, NEW YORK.

DESIGN FOR A BEDSTEAD END FRAME.

Application filed February 7, 1923. Serial No. 5,110. Term of patent 3½ years.

To all whom it may concern:

Be it known that I, JAMES H. DYETT, a citizen of the United States, residing at Buffalo, in the county of Erie and State of New York, have invented a new, original, and ornamental Design for a Bedstead End Frame, of which the following is a specification, reference being had to the accompanying drawing, forming a part thereof.

The accompanying drawing shows a perspective view of a bedstead end frame embodying the design.

I claim:

The ornamental design for a bedstead end frame, substantially as shown.

February 3, 1923.
